UNITED STATES PATENT OFFICE.

JAMES F. LOUCKS, OF CLEVELAND, OHIO, ASSIGNOR OF ONE-HALF TO HARRY GILLETT,
OF GATES MILLS, OHIO.

CLAMPING DEVICE.

Application filed June 6, 1924. Serial No. 718,213.

This invention relates to clamping devices and, while capable of use in other relations, is peculiarly adapted for the purpose of securing to metal beams sheet-metal structural units of the general type shown in application No. 686,493 filed jointly by myself and Harry Gillett on January 16, 1924. The general object of the invention is to provide a simple, economical, and efficient means for securing or clamping such sheet-metal constructions to structural beams. Further and more limited objects of the invention will appear hereinafter and will be accomplished and realized in and through the construction and arrangement of parts shown in the drawings, wherein Fig. 1 represents a sectional view through a sheet metal structure showing the same secured to a beam by means of clamps embodying my invention; Fig. 2 a plan view of a portion of the construction shown in Fig. 1; Fig. 3 a detail in section corresponding to the line 3—3 of Fig. 1; Fig. 4 a detail in perspective of one of the clamps; and Fig. 5 a view, similar to Fig. 3, showing a slightly modified form of the clamp as designed for use with an I-beam.

Describing the various parts by reference characters, and in connection with Figs. 1-4 inclusive, 1 denotes the web and 2 one of the flanges of a channel beam. Supported by this beam is a building-construction unit, the same comprising a metal sheet 3 having projecting downwardly therefrom hollow ribs 4, the said ribs being triangular in section and the tops of the ribs being substantially closed whereby the upper surface of the sheet 3 will be substantially continuous or uninterrupted while the bottom of the sheet will be provided with triangular ribs which are adapted to rest upon the tops of structural beams and which may receive therebetween fibrous insulating material. The details of construction of the structural unit and the purposes and advantages of the same are fully set forth in the aforesaid application, the clamping means shown herein being particularly designed for securing units or sheets of this general character to the structural beams on which they are supported by the hollow ribs.

Each clamp is made of sheet metal and comprises generally an intermediate resilient spacing and supporting portion, tongues or

securing members projecting from one edge 55 thereof for securing the same to the said sheet or unit, and beam-engaging means projecting from opposite ends thereof. The intermediate portion is bent or corrugated to permit the beam-engaging portions of the 60 member to be sprung apart for application to a beam.

5 and 5^a denote the end portions, which portions are connected by an intermediate portion comprising a corrugated or V-shaped 65 central section or portion 6 and shorter reversely-corrugated or V-shaped portions 7 located between the portion or section 6 and the end portions 5 and 5^a. The portions 6 and 7 are of a width equal to the depth of the 70 ribs 4, whereby the sheet will be supported upon the beam by means of the ribs 4 and the portions of the clamping members intermediate the ends 5 and 5^a. The end portion 5 is provided with a downward extension 5^c 75 having a straight edge 5^d which is adapted to engage the web 1 of a channel beam. The end portion 5^a is provided with an extension 5^e which is adapted to engage beneath the flange 2 of a channel beam, the upper edge 80 5^f of such extension having a configuration which will enable it to contact with the lower surface of such flange. Between the extension 5^e and the adjacent corrugation 7 a straight edge 5^g is provided which is 85 adapted to engage the outer edge of the flange 2.

Projecting from the corrugations 7 are the prongs or tongues 8, the said prongs or tongues being located on the upper edge of 90 the clamping member—that is to say, the edge which is opposite the projections 5^c and 5^e.

With the parts constructed and arranged as described, the clamping members will be 95 slipped over the ends of the channel beams, with the projection 5^e arranged beneath a flange 2 of a beam, springing the clamping members open a sufficient distance to enable the extensions 5^c to engage the web 1 of the channel, the distance between the edges 5^d and 5^g being slightly less than the width of the flanges 2 whereby the clamping members, when applied, will be retained in place by friction. The clamping members having 100 been thus applied, the sheets 3 are applied to the beams. With a proper punch, the sheet will be driven down upon the tongues 105

8, which will puncture the sheet, after which the tongues will be bent over and flattened down, as shown in the drawing.

In Fig. 5 there is shown a modification of the form of clamping member shown in the preceding views and which is adapted for use with I-beams and T-beams as well as with channel beams, the web of the I-beam being indicated at 9 and the flanges at one end being indicated at 10. In this case, the clamps will be of the same shape as shown in the preceding views except that the edge 5^a will be provided with a shallow notch 5^b to receive the edge of the adjacent flange 10. In all other respects, the clamping members to be used with the I-beam will be identical with those which are used with the channel beams.

Where it is desirable to use only a single form of clamp, the one shown in Fig. 5 will be used, since it is adapted for application to channel beams, I-beams and T-beams.

For convenience of description the sheets 3 are assumed to be applied to the tops of 25 the structural beams, with the clamping members resting on top of the beams and interposed between the same and the lower surfaces of the said sheets; and the terms "upper" and "lower" have been employed in 30 the description and claims to set forth the relative positions of the parts but without thereby limiting my invention to a construction wherein the positions of the beams and of the sheets may not be other than those 35 specifically shown and described herein.

By making the central portion 6 resilient and giving it a form of the character shown herein, the clamps and the sheet 3 secured thereto will be retained by friction upon the beams to which the clamps are applied, even though one end of each such beams may be considerably lower than the other, as is the case with beams employed in roofing construction. Furthermore, one size of clamps 45 or clips may be used with beams of varying width.

Having thus described my invention, what I claim is:

1. As an article of manufacture a clamp 50 for fastening a sheet to a flanged support, said clamp comprising a resilient sheet metal body having at each end thereof a projection, one of said projections being hooked to engage beneath such flange and the other projection being arranged to engage the part 55 of the beam opposite such flange, the intermediate portion of such sheet metal body having an edge adapted to rest upon the beam and an opposed edge adapted to engage such sheet, such intermediate portion being deflected thereby to provide an extended bearing on said beam and place the end portions of the clamp under tension,

the opposite edge of such body being provided with one or more integral tongues for 65 fastening the sheet thereto.

2. As an article of manufacture, a clamp 70 adapted to fasten a metal sheet to a structural beam, said clamp comprising a resilient sheet metal body having at each end thereof a projection, one of said projections being hooked to engage beneath a flange of a beam, and the other projection having a vertical face with a notch therein, whereby 75 such second projection is adapted to engage the web of said beam, the intermediate portion of such sheet metal body having an edge adapted to rest upon the beam and an opposed edge adapted to engage such sheet, such intermediate portion being deflected 80 thereby to provide an extended bearing on said beam and place the end portions of the clamp under tension, the opposite edge of such body being provided with one or more integral tongues for fastening the sheet 85 thereto.

3. As an article of manufacture, a clamp 90 for securing a metal sheet to a structural beam, said clamp comprising an intermediate spacing and supporting portion, means 95 projecting upwardly from each end thereof for securing the same to a metal sheet and beam engaging portions projecting downwardly therefrom for securing said clamp to a beam, said intermediate portion being bent 95 to permit the beam engaging portions to be sprung apart for application to said beam.

4. As an article of manufacture, a clamp 100 for securing a metal sheet to a structural beam, said clamp comprising a body portion 105 having corrugations therein and being provided at opposite ends with securing members for securing the same to a strip of sheet metal and beam engaging members projecting downwardly from the opposite 105 ends thereof and adapted to be sprung apart for application to said beam.

5. As an article of manufacture, a resilient sheet metal clamp for fastening a sheet 110 to a support, said clamp comprising a body 115 portion having one edge adapted to engage a surface of said support and being provided with a pair of projections extending from such edge and adapted to engage the opposite sides of such support, the opposite edge 115 of the said clamp being provided with means for attaching the same to the sheet to be so fastened to the said support, the said body portion being deflected between the said projections whereby the support-engaging projections may be sprung apart for application 120 to such support.

In testimony whereof, I hereunto affix my signature.

JAMES F. LOUCKS.
